US00D797062S

(12) **United States Design Patent** (10) **Patent No.:** **US D797,062 S**
(45) **Date of Patent:** **** Sep. 12, 2017**

(54) **DIMMER SWITCH**

(71) Applicant: **Lutron Electronics Co., Inc.**,
Coopersburg, PA (US)

(72) Inventors: **Susan Hakkarainen**, Doylestown, PA
(US); **Jason C. Killo**, Emmaus, PA
(US); **Matthew Philip McDonald**,
Phoenixville, PA (US)

(73) Assignee: **Lutron Electronics Co., Inc.**,
Coopersburg, PA (US)

(**) Term: **15 Years**

(21) Appl. No.: **29/557,519**

(22) Filed: **Mar. 9, 2016**

(51) **LOC (10) Cl.** **13-03**

(52) **U.S. Cl.**

USPC **D13/170**

(57) **CLAIM**

The ornamental design for a dimmer switch, as shown and
described.

DESCRIPTION

FIG. 1 is a front perspective view of a dimmer switch
showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines represent structure or features
which form no part of the claimed design; the broken lines
themselves form no part of the claimed design.

1 Claim, 2 Drawing Sheets
